UNITED STATES PATENT OFFICE

HALBERT K. HITCHCOCK, OF PITTSBURGH, PENNSYLVANIA, ASSIGNOR TO PITTSBURGH PLATE GLASS COMPANY, A CORPORATION OF PENNSYLVANIA

GLASS-SURFACING APPARATUS

Application filed April 22, 1925. Serial No. 25,007.

The invention relates to glass surfacing and more particularly to means for securing the plates or sheets to be surfaced to the cars or tables employed in a straight away grinding and polishing operation. It has for its primary objects: the provision of an improved form of vacuum holding apparatus whereby the necessity of using plaster of Paris for securing the plates to the cars or tables is avoided; the provision of a simple and effective arrangement whereby the necessary vacuum or suction effect can be applied to each table of the series separately as the glass is placed thereon, and can also be applied to the entire series ahead of the table upon which the glass is being positioned with the result that any leakage in the system can be compensated for each time a table is added to the train or series; the provision of an arrangement whereby the vacuum systems of all the cars or tables are automatically coupled together when the cars are brought into abutting relation, so that by coupling the suction apparatus to any car, the entire system may be exhausted; the provision of an arrangement whereby suction is applied automatically to the table upon which a glass sheet has been positioned by the mere act of coupling such car to the other cars constituting the train; and the provision of improved means for coupling the exhaust systems of the successive cars together and for coupling the exhaust producing apparatus to the exhaust systems of the cars so that the number of coupling devices required is reduced to a minimum, and the work of the operator made simple and easy. Certain embodiments of the invention are illustrated in the accompanying drawings, wherein:

Figure 1 is a plan view of the assembled apparatus. Fig. 2 is an enlarged horizontal section taken through the coupling devices at one end of one of the tables. And Fig. 3 is a modification of the coupling arrangement shown in Fig. 2.

Referring to Fig. 1, the reference numerals 1, 2, 3, 4 and 5 designate a series of tables or cars mounted for movement along a track for carrying the tables beneath a series of grinding and polishing machines in order to sur-

face the sheets of glass secured to the upper faces of the tables or cars.

The apparatus for securing the necessary vacuum or suction effect is located at one side of the track upon which the cars are mounted and comprises an electric motor 6 driving a vacuum pump 7, such pump being connected to a suitable vacuum tank 8. A pair of hose connections 9 and 10 are connected into the tank and carry at their ends suitable nozzles 11 for insertion into the coupling members carried by each of the cars.

The cars are all similarly constructed and each consists of a top member 12 supported upon wheels and provided with a flat, smooth glass supporting surface 13 upon which the glass plates to be surfaced are positioned. The supporting surface 13 is provided with a plurality of shallow sets of grooves 14 leading into the ends of the vertical passages or communications 15 which extend down to the longitudinal connections 16 and 17, the connections 16 and 17 being connected by the pipe 18. Each connection 17 extends to both ends of the table, as indicated in Fig. 1, having at one end the single branch 19 and at the other end, the pair of branches 20 and 21. The branch 21 being arranged so that it comes into alignment with the branch 19 on the next car, while the branch 20 leads through the side of the car and receives the nozzle 11 carried by one of the pipes 9 or 10, as heretofore referred to.

The details of the branch connections at the ends of two of the cars is shown in Fig. 2 on an enlarged scale. Referring to this figure, the branch 19 is provided with a coupling member 22 having a valve seat at 23 and carrying a check valve 24 normally held in closed position by the spring 25. The branch connection 21 on the opposing car end is provided with a valve seat 26 and carries a valve 27 normally held in closed position by the spring 28. The branch 21 also carries a cap 29 clamping in position the rubber sleeve 30, for making a tight contact with the coupling member 22. The check valve 24 is provided with a stem 31 normally projecting beyond the outer end of the coupling member 22, so that when the parts are brought into the cou-

90

95

100

pled relation shown, the end of the stem engages the valve 27 and a further movement of approach causes the opening of both check valves, the outer end of the coupling member 22 finally engaging the valve 27 and rendering its opening positive. The outer end of the coupling member 22 is provided with the ports 32, so that when the parts are in the coupled relation shown, communication is established between the exhaust systems of the two cars.

The valve 27 has its middle portion slotted, as indicated at 33, thus providing for the passage of the nozzle 11 when the pipe 9 is coupled to the car 3. In reaching the position shown in Fig. 2, the nozzle 11 opens the check valve 34 normally held shut by the leaf spring 35, the check valve when thus moved out of the way by the nozzle occupying the dotted line position, as indicated in the drawing. A tight connection is insured between the end of the nozzle 11 and the part 21 by means of the rubber sleeve 36 clamped between a flange 37 on the part 21 and the cap 38, such cap being connected to the longitudinal connection 17. A tight connection is also secured between the nozzle 11 and the cap member 39 just below the check valve 34 by the use of the rubber sleeve 40 clamped between the cap 39 and the nut 41.

When the nozzle is pushed in to the extreme position illustrated in Fig. 2, the exhausting of air through the nozzle and pipe 9 produces a vacuum in the systems of the tables 1, 2 and 3 and in all of the systems of the cars to the right of the car 3. At this time, there is no communication from the nozzle 11 to the exhaust system of the car 4, but if a sheet of glass has just been laid upon this car and it is desired to apply suction to the system of the car, this can be done by inserting the nozzle of the hose 10.

However, it is not necessary to apply this separate nozzle to the car 4 in order to secure the desired vacuum, as this may be done by merely coupling the car to the car 3 provided the nozzle 11 is at this time removed and the valve 34 allowed to close. Under these conditions, the exhaust or suction effect present in the train of cars 1, 2, 3, etc. is immediately communicated to the connections of the car 4 when such car is brought into coupled relation with the car 3, thus opening the two check valves 24 and 27.

Suction may be also applied to the system of the car 4 from the nozzle 11 on the hose 9 by merely withdrawing such nozzle until its end lies at the point marked *a*. In such position, the nozzle 11 does not interfere with the communication between the passage 42 and the interior of the sleeve 22, the ports 32 permitting such communication. When the nozzle 11 is in the position just referred to with its end at the point *a*, the application of suction through the nozzle applies suc-

tion to all of the cars of the train, that is, to the cars 3, 2, 1, etc. in advance of the nozzle connection and to the cars 4, 5, etc. to the rear of such nozzle connection. It is thus possible by inserting the nozzle 11 into the lateral branch 21 of any of the tables to apply exhaust to the entire system of tables and thus compensate for any loss of vacuum in the system due to leakage. A hand valve 43 just back of the nozzle 11 serves to cut off any back flow through the pipe 9 when the nozzle is withdrawn from the branch 21.

Fig. 3 illustrates a modified arrangement of coupling connections and check valves for accomplishing substantially the same functions as those described in connection with the Fig. 2 construction. In this construction, the end of the car is provided with a coupling member 44 adapted to telescope into the coupling member 45 on the car 3. The member 44 carries a check valve 46 normally held closed by the spring 47, but adapted to be moved to open position by means of the lever 48 pivoted at 49 upon a suitable bracket and having its inner end in pivotal connection with the stem of the valve 46. The coupling member 45 is also provided with a check valve 50 normally held in closed relation by the spring 51, but adapted to be opened by the bell crank lever 52 pivoted at 53 and having one end in operative engagement with the stem 54 of the valve 50. The stem 54 of the valve 50 is adapted to engage the lever 48 and open the check valve 46 when the cars are brought into the coupled relation as indicated in the drawing. The end of the coupling member 44 is beveled as indicated at 55, so that when this member is brought to the position illustrated, it engages the end of the lever 52 and moves the valve 50 to open position, so that the exhaust systems of the two cars or tables are brought into communication automatically when the cars are coupled. In order to make a tight connection between the coupling member 44 and the coupling member 45, the rubber sleeve 56 is employed, such sleeve being clamped between the end of the member 45 and the nut 57.

The exhaust pipe 9 is provided at its end with a coupling member 58 and such coupling member carries a check valve 59 normally held closed by the spring 60, such valve being opened by means of the lever 61, pivotally supported at 62 and having its inner end in engagement with the stem of the valve 59. The member 58 is adapted to telescope into the coupling member 63 which also carries a check valve 64 normally held closed by the spring 65. This valve is adapted to be moved to open position by the bell crank 66 pivoted at 67 and having one end engaged with the stem 68 of the valve 64. The end of the member 58 is beveled as indicated at 69, so that when the parts 58 and 63 are brought

into the coupled relation shown, the lever 66 is swung so that it opens the valve 64. At the same time, the end of the valve stem 68 engages the lever 61 and opens the valve 59 so that the coupling of the two parts brings the vacuum pipe 9 into communication with the pipe 70 leading to the suction devices of the table 3. A tight connection is secured between the members 58 and 63 by the use of the rubber sleeve 71 clamped in position between the end of the member 63 and the nut 72. The method of operation and the resulting functions are the same as described in connection with the Fig. 2 construction.

What I claim is:

1. The combination with a plurality of surfacing cars or tables mounted for movement along a track and each having a glass supporting surface, of an exhaust system for each table comprising communications leading down from the surface of the table and connections therefrom extending to each end of the table, coupling devices at each end of each table arranged to couple the ends of the connections at the opposing ends of the cars together in communicating relation when the tables are brought into abutting relation, check valves at the ends of said connections adapted to close when the abutting ends of the tables are separated, an air exhausting apparatus arranged adjacent the track and means whereby said exhausting apparatus may be connected to the exhaust system of each table in turn.

2. The combination with a plurality of surfacing cars or tables mounted for movement along a track and each having a glass supporting surface, of an exhaust system for each table comprising communications extending down from the surface of the table and connections therefrom leading to each end of the table, and provided with check valves yieldingly held closed, coupling devices at each end of each table arranged to open said check valves and couple the ends of the connections on opposing tables together when such tables are brought into abutting relation, an air exhausting apparatus arranged adjacent to the track, and means whereby said exhausting apparatus may be connected to the exhaust system of each of the tables.

3. The combination with a plurality of surfacing cars or tables mounted for movement along a track and each having a glass supporting surface, of an exhaust system for each table comprising communications extending down from the surface of the table and connections therefrom leading to each end of the table, and each having a lateral branch leading to the side of the table, check valves at the ends of said connections and also in said branch connections yieldingly held closed, coupling devices at each end of each table arranged to open said check valves

at the ends of said connections and couple said connections together when the tables are brought into abutting relation, an air exhausting apparatus adjacent the track, and means for coupling said exhaust apparatus to any one of said branch connections.

4. The combination with a plurality of surfacing cars or tables mounted for movement along a track and each having a glass supporting surface, of an exhaust system for each table comprising communications extending down from the surface of the table and connections therefrom leading to each end of the table, and each having a lateral branch leading to the side of the table, check valves at the ends of said connections and also in said branch connections yieldingly held closed, coupling devices at each end of each table arranged to open said check valves at the ends of said connections and couple said connections together when the tables are brought into abutting relation, an air exhausting apparatus adjacent the track, and a coupling device for connecting said exhaust apparatus to any one of said branch connections arranged so as to open the check valve in said branch connection.

5. The combination with a plurality of surfacing cars or tables mounted for movement along a track and each having a glass supporting surface, of an exhaust system for each table comprising communications extending down from the surface of the table and connections therefrom leading to each end of the table, and each having a lateral branch leading to the side of the table, check valves at the ends of said connections and also in said branch connections yieldingly held closed, coupling devices at each end of each table arranged to open said check valves at the ends of said connections and couple said connections together when the tables are brought into abutting relation, an air exhausting apparatus adjacent the track, and a coupling device for connecting said exhaust apparatus to any one of said branch connections arranged so as to open the check valve in said branch connection, the said coupling device when in one position cutting off communication between the exhaust systems of the two abutting tables and in another position permitting such communication.

6. The combination with a surfacing car or table mounted for movement along a track and having a glass supporting surface, of an exhaust system for the table comprising a communication extending down from the surface of the table, a longitudinal passage connected thereto and extending to the ends of the tables, and a lateral branch passage extending to the side of the table, a check valve in said branch passage and also in each end of said longitudinal passage, all yieldingly held in closed position, and an exhausting device provided with a pipe having a cou-

pling member at the end thereof adapted to fit into said branch passage and open the check valve in such branch passage.

In testimony whereof, I have hereunto subscribed my name this 13th day of April, 5 1925.

HALBERT K. HITCHCOCK.
